ELECTRIC NAIL POLISHING MACHINE

Filed Feb. 20, 1922

UNITED STATES PATENT OFFICE.

HARRY LARRÚS AND LOUIS KRAUSE, OF NEW YORK, N. Y.

ELECTRIC NAIL-POLISHING MACHINE.

Application filed February 20, 1922. Serial No. 537,971.

To all whom it may concern:

Be it known that we, HARRY LARRÚS and LOUIS KRAUSE, citizens of the United States and of Russia, respectively, and respectively 5 residing at New York city, borough of Manhattan, New York County, N. Y., and New York city, borough of the Bronx, in the county of Bronx and State of New York, have invented certain new and useful 10 improvements in Electric Nail-Polishing Machines, of which the following is a specification.

This invention relates to toilet articles or appliances and has particular reference to 15 manicuring apparatus.

Among the objects of the invention is to provide a machine for the rapid and efficient polishing of finger nails, a machine such as is of peculiar advantage and merit in beauty 20 parlors or manicuring establishments, and through the use of which the manicuring operation may be performed exceedingly rapidly and in a manner superior to the operation ordinarily performed by hand.

More specifically stated the invention includes a polishing tool with means for attaching it to a carrier, the latter being mounted for rapid reciprocations to and fro along a predetermined line, and including 25 also a resilient or flexibly supported saddle for supporting the finger in position to have its nail polished as a result of said reciprocations.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

Figure 1 is a side elevation of the main parts of the improvement, parts being in section.

Fig. 2 is a plan view of the same.

Fig. 3 is a vertical sectional detail of the 40 finger support, the section being in a plane parallel to the aforesaid tool carrier.

Fig. 4 is a vertical section on the line 4—4 of Fig. 3.

Fig. 5 is a sectional detail of the casing holding means, on the line 5—5 of Fig. 2.

Referring now more specifically to the

drawings 10 indicates a base, preferably faced beneath with felt 11 or its equivalent to reduce the noise and the possibility of marring of any table or other support upon 60 which the machine may be placed in practice. Handles 12 are attached to the ends of the base for the manipulation of the entire machine. Without being unnecessarily restricted as to size, material, or configuration 65 of the base, suffice it to say that it is of rectangular form as shown, a form found in practice to be very satisfactory.

Adjacent to one end of the base is supported, as upon a bracket 13, a motor M, the 70 shaft 14 of which is transverse to the longer axis of the base. Any suitable source of electric energy may be provided, the same being indicated by the wires 15 connected in a socket 16 formed on or attached to the base 75 and adjacent to which is any suitable type of switch 17 for starting and stopping the motor in any well known manner.

A pulley 18 is attached to the motor shaft 14, and arranged in alignment with the pulley 18 is a larger pulley 19 fixed to the shaft 20 of a crank wheel 21 having a wrist pin 22. The shaft 20 is suitably journaled in a bearing 23 supported upon a pedestal 24. The motor and other high speed parts associated therewith are preferably covered or protected by a casing 25 of L-shape in plan view, one portion of the casing directly covering the motor and the other portion covering the crank wheel and adjacent parts, 80 leaving space within the angle of the casing for the socket 16 and switch 17. The casing is secured in place preferably by the provision of a series of lugs or feet 26 extending outward from the lower edge of the casing 85 and with their lower faces in direct contact with the top of the base. Each of these feet carries a downwardly projecting pin or stud 27 shown as a screw tapped directly into the foot and extending freely into a hole 28 90 formed in the base, the head of the pin or screw projecting upward above the foot. Co-operating with this head is a spring clip 29 attached permanently to the base by means of a pivot 30 and having a hole 31 95 which receives the head of the pin 27 when the clip is brought over the foot as shown. These clips 29 are strong and stiff enough to hold the casing down firmly upon the base, and movement in any horizontal direction is 100 prevented by the pins 27 in the holes 28 and the engagement between the clips and the

heads of the pins. To remove the casing for access to the motor the clips may be swung around as suggested in dotted lines in Fig. 2 leaving all of the feet free to be lifted with 5 the casing from the position stated.

32 indicates a carrier shown as a straight bar mounted for reciprocations to and fro in the same path, and supported upon two spaced uprights 33 each having a base 34 secured upon the base 10, and each upright being provided with a pair of spaced rollers 35 between which the bar is supported anti-frictionally. To one end of the bar or carrier 32 is pivoted at 36 a connecting rod 37 10 whose other end is mounted on the wrist pin 22.

Connected in any suitable manner to the carrier, as by means of a clamp 38 having thumb nuts 39, is a tool 40 shown as a burs- 20 nisher of any suitable construction or design. The connection between the tool and the carrier is such that the active surface of the tool will be reciprocated coincident with the reciprocations of the carrier as a 25 result of the connection between the carrier and the crank wheel 21. The rollers 35 compel the carrier to move to and fro in substantially the same line. Because of the nature of the clamp 38 the tool may be 30 readily removed or interchanged as may be required by the operator.

Located directly beneath the tool 40 and midway between the uprights 33 is a finger support 41. This construction includes a 35 pedestal 42 fixed rigidly in any suitable manner upon the base 10 as through a disk 43 and having a vertical central bore 44. Mounted within this bore and adjustable up or down therein is a screw 45 provided 40 however with means to prevent rotation of the screw in the pedestal. This means is indicated as a pin or screw 46 fixed laterally into the screw and projecting into a vertical slot 47 formed in one side of the pedestal. 45 Fixed to or otherwise forming a part of the pedestal are a plurality of keepers 48 shown as secured to opposite sides of the pedestal by means of screws 49. These keepers include hooks or ends turned inward toward 50 the axis of the screw 45 and spaced upward from the other portions of the pedestal, providing a space 50 within which is loosely fitted a nut 51 having a knurled periphery through direct contact with which the operator 55 causes the screw to move up or down. The nut 51 is held resiliently up against the points of the keepers as by means of a coil spring 52 whose lower end is supported in an annular recess 53 formed in the pedestal. 60 The nut 51 occupies only a portion of the space 50, leaving a sufficient space below the nut for the screw to move downward against the force of the spring during the use of the machine. Fixed suitably to the upper end 65 of the screw is a finger rest 54 which in

practice is spaced below the tool 40 to admit the customer's finger or thumb with the nail thereof directed toward the tool. The resiliency of the spring and the space 50 afford ample accommodation for the customer's 70 finger, subject as may be required to adjustment of the screw up or down to suit various sizes of fingers and also possible variations in depth of the working surface of the tool beneath the carrier 32. With the nut 51 held normally upward against the upper ends of the keepers 48, by the action of the spring 52, it follows that rotation of the nut 75 co-operating with the screw thread will cause the screw and finger rest to move either up or down according to the direction of rotation of the nut, the screw being held from rotation by the pin 46. In all reasonable positions of adjustment of the screw and finger rest the nut and screw are free 80 to move downward resiliently as far as permitted by the free space 50 below the nut, and furthermore it will be noted that the force of the spring remains constant irrespective 85 of the elevation of the screw and finger rest. With the finger rest adjusted in accordance 90 with the approximate size of the customer's fingers, the customer, seated on one side of the base 10, will put his fingers in succession into the cavity at the top of the rest with the nails thereof in proximity to the tool 40, the spring 52 permitting the rest to move 95 downward slightly so as to maintain a fair degree of frictional contact between the customer's nail and the active surface of the tool. With the machine in operation it follows that the nail will be quickly polished and so on with all of the other nails in rapid succession. The operator of the machine naturally is positioned on the opposite side 100 thereof from the customer and controls the operation of the machine.

We claim:

1. In a nail polishing machine, the combination with a polishing tool, of a rigid 110 bar constituting a carrier to which said tool is fixed, means to reciprocate said carrier and tool, and means for guiding and supporting the carrier to compel it to move 115 to and fro in the same path, said last mentioned means including a pair of uprights having anti-friction rollers for co-operation with the carrier.

2. In a nail polishing machine, the combination of a base, a pair of uprights extending upward therefrom, spaced rollers in the uprights, a bar supported between said rollers, power means to reciprocate the bar, a 120 casing for covering the power means, and a polishing member carried by said bar.

3. A device as set forth in claim 2 in which the power means is an electric motor and the casing is provided with separable clips for locking it to the base from movement in any 125 direction.

4. In a nail polishing machine, the combination with a base, a motor thereon, and a casing inclosing the motor, of means for locking the casing to the base and including
5 a plurality of lugs fixed to the casing, pins secured in said lugs and extending downward therefrom into holes in the base and also having heads above the lugs, and clips pivoted to the base and movable over the
10 lugs and pin heads, the clips having holes to receive said heads.
5. A finger support for nail polishing machines comprising a pedestal having a smooth central bore, a screw fitted movably
15 in said bore, means to hold the screw from rotation in the bore, a finger rest carried by the upper end of the screw, a pair of keepers fixed to the pedestal and extending in the form of hooks in spaced relation above the top of the pedestal, a nut threaded upon 20 the screw and located within said space, and a coil spring surrounding the screw and pedestal and bearing upward against the nut holding it normally against said keepers, the nut being rotatable within the space 25 aforesaid for adjusting the finger rest up or down, while the tension on the spring remains constant.

In testimony whereof we affix our signatures.

HARRY LARRÚS.
LOUIS KRAUSE.
